United States Patent

Des. 236,721
Patented Sept. 9, 1975

236,721

COMBINED CLIP BOARD AND SOUND LEVEL METER

Alfred L. Stolberg, Rochester, N.Y., assignor to
Metrosomics, Inc., Rochester, N.Y.

Filed May 23, 1973, Ser. No. 363,028

Term of patent 14 years

Int. Cl. D19—99

U.S. Cl. D19—88

The figure is a perspective view of a combined clip board and sound level meter showing my new design; the surfaces not shown being plain and unornamented.

I claim:

The ornamental design for a combined clip board and sound level meter, substantially as shown and described.
